UNITED STATES PATENT OFFICE.

BUELL S. BURNETT, OF JACKSONVILLE, FLORIDA.

PERMUTATION-LOCK.

1,163,504.

Specification of Letters Patent.

Patented Dec. 7, 1915.

Application filed July 31, 1915. Serial No. 42,978.

To all whom it may concern:

Be it known that I, BUELL S. BURNETT, a citizen of the United States, residing at Jacksonville, in the county of Duval and

5 State of Florida, have invented new and useful Improvements in Permutation-Locks, of which the following is a specification.

This invention relates to improvements in permutation locks, proposing a construction 10 of the broad or general type disclosed in my U. S. Patent No. 1,036,653 of April 20, 1915, the salient structural features of which are a sliding bolt having projections, ring-like tumblers coöperating with one of the projections 15 on the bolt, and a central main tumbler for operating the ring-like tumblers and for coöperation with another projection on the bolt, all of these elements being fitted within a lock casing and the main tumbler 20 being connected with a rotatable operating knob and dial plate.

The principal objects of the present invention are to provide a lock of the type identified which, in comparison with the 25 construction shown in my said patent, shall be simpler in its details of construction and organization, which may be manufactured with greater facility and at less expense, which shall be more compact, and, hence, 30 capable of a greater number of practical adaptations, which shall be more readily accessible for such purposes as may be required, and the parts of which may be adjusted for the purpose of varying the combination with the greatest ease and facility.

35 The above objects and advantages will appear as the description proceeds.

An embodiment of the invention is illustrated in the accompanying drawings, 40 wherein:—

Figure 1 is a front elevation of the improved lock, the bolt being projected; Fig. 2 is a rear elevation thereof with the back plate and the adjoining tumbler removed to expose to view the inclosed parts; Fig. 3 is a view similar to Fig. 2, but showing only the back plate removed and the bolt retracted; Fig. 4 is a vertical central sectional view showing the bolt retracted; Fig. 5 is 45 a view similar to Fig. 4, but showing the bolt projected; Fig. 6 is a horizontal sectional view on the line 6—6 of Fig. 4; Fig. 7 is a sectional view in the plane of the lock showing more particularly the relation 50 between the main tumbler and the sliding

bolt; Fig. 8 is a detail sectional view on the line 8—8 of Fig. 7; Fig. 9 is a composite perspective view showing in disassembled relation the various elements of the lock.

Similar characters of reference designate 60 corresponding parts throughout the several views.

The operating elements are assembled with relation to a base plate 1 having at its margin a forwardly projecting flange 2 and 65 which, in combination with a back plate 3 and spacing rings 4 and 5, provides the case of the lock. These parts are here shown as circular, but they may have any desired size and shape. The back plate 3 is secured by 70 screws which take into the base 1 and pass through openings in the rings 4 and 5 (see Fig. 6) and the rings 4 and 5 are secured against the base plate 1, preferably, by 75 rivets 6 (see Figs. 7 and 8), although screws may be used, if desired. The lock includes a sliding bolt 7 which is co-planar with the body or major portion of the plate 1 and is movable radially in a slot 8 extending from 80 a central enlarged opening 9 formed in said plate to an annular depressed portion 10 which connects the body of the plate 1 and the flange 2. The latter has a peripheral slot 11 in line with the radial slot 8 and through which the head 7^a of the bolt 7 85 projects.

The bolt 7 is projected by a main tumbler 12 against the tension of a coil spring 13, one end of which is connected to the bolt and the other end of which is connected 90 to the flange 2. The retraction of the bolt is controlled by the main tumbler 12 and by a pair of ring-like tumblers 14 and 15, hereafter, for convenience, termed "ring" tumblers.

The flange 2 provides a housing for a plate 16 hereafter called a dial plate and which is fitted against the plate 1. The plate 16 is provided with a marginal flange 17 which closely fits the inner circumferential face of the flange 2, the outer face of which is flush with the front edge of said flange 2. The flange 17 carries the dial indications, these being moved across an indicating point or line 18 formed on the front of the flange 2. The dial plate 16 and the main tumbler 12 are rotated by an operating knob 19 having a flat-sided, preferably octagonal, arbor 20 which passes through conformable 100 central openings in the plate 16 and in the 105 plate 16.

tumbler 12. The tumbler 12 has its margin, except for a recess to be hereafter described, of annular curvature and is co-planar with the plate 1, fitting within the opening 9 of said plate. The tumbler 12 is held upon the arbor 20 by a nut 21 which engages on a threaded stud 22 projecting from the inner end of the arbor 20.

For the purpose of correlating the tumbler 12 and the bolt 7, said tumbler has a radial recess 23 of general V-form which extends from the central opening of the tumbler to the annular curved margin thereof and the bolt has its lower edge formed with a projection 24 which, when the bolt is retracted, enters fully into the recess, as shown in Fig. 7, and when the bolt is projected, rides or bears upon the annularly curved marginal portion of the tumbler. To project the bolt 7, the tumbler 12 is rotated in either direction from the position shown in Fig. 7, and in accordance with its direction of rotation, either of the inclined sides of the recess 23 will engage the projection 24, and, exerting a cam action thereon, will raise or project the bolt in the obvious manner. The depressed portion 10 of the plate 1 provides for a disk-shaped recess or counter-sink 25 at the rear side of said plate which has the same diameter as the ring tumbler 14 and in which said tumbler is fitted directly against the rear side of the plate 1. The tumbler 14 is provided at the margin of its central opening with a pair of oppositely disposed projections 26 which are directed toward the rear plate 3. The tumbler 15 is provided at the margin of its central opening with a pair of oppositely disposed radial co-planar projections 27 which, in the course of the rotation of the tumbler 14, are engaged by the projections 26. The projections 26 are, in turn, engaged by oppositely disposed projections 28 which are functional parts of the main tumbler 12, but, as a matter of convenience, are formed on a plate 29 fitted on the arbor 20 for rotation therewith and held against the rear face of the main tumbler 12 by the nut 21. The plate 29 is of greater diameter than the tumbler 12 and its marginal portion bears against the rear face of the plate 1 and thereby retains the plate 16 and the tumbler 12 in position.

The tumbler 14 is confined in its seat 25 by the ring 4. The ring 5 fits directly against the ring 4 but is of less width than the ring 4, whereby the two rings, in conjunction, provide an angular seat 30 for the tumbler 15, said tumbler fitting within the central opening of the ring 5, co-planar with said ring.

The bolt 7 is correlated to the tumblers 14 and 15 by a lateral projection 31 which, when the bolt is retracted, enters into aligning marginal recesses of said tumblers. To increase the number of possible combina-

tions, each of the tumblers 14 and 15 has a pair of marginal recesses, those of the tumbler 14 being designated 32 and 33, and those of the tumbler 15 being designated 34 and 35. The recesses 32 and 33 are located at the same side of and in adjacency to a diameter of the tumbler 14. A similar arrangement is carried out for the recesses 34 and 35. The manner in which the tumblers 14 and 15 are adjusted relatively to one another to vary the combination will be described later. For the present, it may be assumed that a flat face X of the tumbler 15 adjoins the back plate 3 and that the combination is such that the recess 34 of the tumbler 15 will align with the recess 32 of the tumbler 14.

The rings 4 and 5 have their central openings provided with outwardly directed recesses 36 and 37 into which the projection 31 of the bolt 7 enters in the retracted relation of said bolt, as shown in Fig. 2.

In assembling the parts, the tumbler 14 is fitted in its seat 25 and the rings 4 and 5 are thereupon connected to the plate 1, the ring 4 being in adjacency to said tumbler. The unit composed of the knob 19, the dial plate 16 and the tumbler 12 is next fitted in position, the dial plate being fitted against the front side of the plate 1 and the tumbler 12 being fitted in the opening 9 of said plate with its recess 23 in alignment with the projection 24 of the bolt 7. Thereupon the plate 29 is fitted on the arbor 20 and against the rear face of the plate 1 and the nut 21 is backed against the plate 29. The tumbler 14 is then turned to bring one of its marginal recesses into line with the projection 31 of the bolt 7 and the bolt is thereupon retracted by its spring 13. The tumbler 15 is next fitted against its seat 30 and within the ring 5, with one of its marginal recesses in alignment with the projection 31, after which the rear plate 3 is attached by its securing screws.

In operating the lock, assuming that the parts are in the positions represented in Figs. 3 and 4, with the bolt retracted, rotation of the knob 19 in either direction will, through the intermediary of the tumbler 12, project the bolt in the manner explained, the projection 24 of the bolt riding on the annularly curved margin of the tumbler 12. Continued rotation of the knob 19 will cause the tumblers 14 and 15 to move, whereby their marginal recesses become out of alignment with one another and with the projection 31, the tumbler 14 being first moved consequent to the engagement of its projections 26 by the projections 28 of the plate 29 and the tumbler 15 being thereafter moved consequent to the engagement of its projections 27 by the projections 26 of the tumbler 14. The bolt will then be maintained in its projected position, and cannot be retracted until the recess 23 of the tum-

bler 12 alines with the projection 24 and the marginal recesses of the tumblers 14 and 15 aline with one another and with the projection 31 of the bolt 7 synchronously with the alinement of the recess 23 and the projection 24 of said bolt.

To effect the withdrawal of the bolt, assuming that a definite combination has been decided upon, and further assuming that the 10 recesses 34 and 32 of the tumblers 15 and 14 are to be moved into alinement with one another and with the projection 31 of the bolt 7, the operation is, of course, the reverse of that just described, and is, in brief, as 15 follows: The dial is first rotated either to the right or to the left, according as the particular combination calls for, until the figure thereon corresponding to the first figure of the combination comes under the indicating point 18. This rotation is transmitted from the dial plate directly to the plate 29, and thence successively to the tumblers 14 and 15, the recess 34 in the latter tumbler being brought into alinement with 25 the projection 31 of the bolt 7 exactly at the moment when the aforesaid figure on the dial alines with the indicating point. Rotation of the dial plate is then reversed and continued until the dial figure corresponding 30 to the second figure of the combination comes under the indicating point, at which time, the recess 32 in the tumbler 14, is brought into alinement with the projection 31 of the bolt 7, and consequently into registration with the notch 34 of the tumbler 15; the tumbler 15 first set remaining stationary owing to the fact that the projections 26 move away from instead of toward, the projections 27, due to the reverse direction of 40 rotation. Finally, the dial plate is again rotated in the same direction as during its initial actuation, until the figure thereon corresponding to the third and last figure of the combination comes under the indicating point 18, thereby bringing the recess 23 of the tumbler 12 under the projection 24 of the bolt, whereupon said bolt is automatically forced inward by the action of its spring 13, the projections 28 of the plate 29 moving away from the projections 26 of the tumbler 14 and leaving the latter idle.

Owing to the octagonal cross-section of the arbor 20 and to the conforming outlines of the central openings of the dial plate 16, 55 the tumbler 12 and the plate 29 which are fitted on said arbor, it will be apparent that the dial plate, the tumbler 12 and the plate 29 are operatively coupled together whereby during the continuance of any given combination they occupy relatively fixed positions; on the other hand, such positions may be varied at will by simply removing the nut 21 and moving either the plate 29 or the tumbler 12 relatively to one another, the 60 nut 21 being thereafter backed against the

plate 29 to hold the parts in position. Each change in the relative positions of the plate 29 and the tumbler 12 will, however, necessitate a new combination, as will be obvious. The combination may be changed, however, with even greater facility by moving the tumbler 15 relatively to the tumbler 14. In the foregoing description of operation, it is assumed, for the purpose of illustration, that the tumbler 15 has a flat side X 75 adjacent the back plate 3 and that its recess 34 is to be alined with the recess 32 of the tumbler 14 upon the completion of the first and second movements of the dial plate. The tumbler 15 may, however, be moved relatively to the tumbler 14 for the purpose of varying the combination in the following ways: First, while having its side X adjacent the back plate 3, the tumbler 15 may be moved whereby upon the completion of 80 the second movement of the dial plate its recess 35 will aline with the recess 32 of the tumbler 14. Or, the tumbler 15 may be set so that its opposite flat face Y is adjacent the back plate 3 and, when so set, may occupy either of two positions, in one of which its recess 34 will aline with the recess 32 of the tumbler 14 upon the completion of the second movement of the dial plate, and in the other of which its recess 35 will aline 85 with the recess 32 of the tumbler 14 upon the completion of the second movement of the dial plate. The tumbler 15 may thus be set in four different positions wherein either of its recesses 34 or 35, as the case may be, 90 will aline with the recess 32 of the tumbler 14. Thus, four different combinations are possible by varying the position of the tumbler 15 relatively to the recess 32 of the tumbler 14. 95

Other changes and combinations may be made by setting the tumbler 14 so that its recess 33 will aline with the bolt 31 upon the completion of the first movement of the dial plate and the tumbler 15 may be, in 100 like manner, set in any one of four different positions relative to the recess 33 of the tumbler 14; that is, when the side X of the tumbler 15 adjoins the plate 3, the tumbler 15 may be set in either of two positions 105 whereby upon the completion of the second movement of the combination either its recess 34 or its recess 35 will aline with the recess 33 of the tumbler 14, or, the tumbler 15 may be positioned with its face Y adjacent the back 110 plate 3, and when so arranged, may be set in either of two positions in which its recess 34 or 35, as the case may be, will, upon the completion of the second movement of the dial plate, aline with the recess 33 of the 115 tumbler 14. Thus, the tumbler 15 may be set in four different ways with relation to either of the recesses 32 or 33 of the tumbler 14 and by such relative adjustments of the tumblers 14 and 15, eight changes in com- 120 125 130

bination are possible when the tumblers 14 and 15 are constructed as shown. The possible combinations may be multiplied indefinitely by other changes, in the manner already described, in the relative positions of the tumbler 12 and the plate 29.

In connection with the operation of the lock to provide for the retraction of the bolt 7, it is to be noted that during the manipulation of the dial plate, the V-shaped or pointed projection 24 on the bolt rests or rides on the peripheral edge of the main tumbler 12, which said main tumbler thereby holds the bolt so that its projection 31 is spaced from the peripheral edges of the tumblers 14 and 15 and also prevents said projection 31 from entering the recess in the ring tumblers 14 and 15, or either of them, until the setting of the tumblers has been completed. In this way, it is impossible for the operator to determine by "feeling" when the recesses are brought under the projection, so that no assistance is thus given to an unauthorized or improper manipulation of the lock 25 to open the same.

The improved lock is capable of an indefinite number of practical applications or adaptations. As shown, it is arranged as a drawer lock and is fitted in an opening A which extends wholly through the drawer, being secured in position by screws B which connect the flange 2 and the wall of the drawer in which the lock is set, as shown in Fig. 7. The drawer has an opening C for the bolt 7 and the drawer casing has a keeper opening D for said bolt, the said openings being preferably provided with face or wear plates e and d, respectively, as is usual.

The improved lock may be manufactured with great facility and economy, not only because the number of parts required is reduced to a minimum and because the parts are of the simplest possible construction, but also because the parts which form the lock casing, the tumblers and the dial plates may be produced by stamping and require no machining. The construction is, moreover, very compact or "thin." This advantageous result is due, in part, to the arrangement of the bolt 7 and of the tumbler 12 in co-planar relation to the plate 1; in part, to the utilization of the spacing rings 4 and 5 as elements of the lock case and to the immediate juxtaposition of these rings; in part, to the perfectly flat construction of the juxtaposed elements; and in part to the co-planar relation of the tumbler 15 to the ring 4, to the arrangement of the tumbler 14 in a counter-sunk seat in the plate 1, and the utilization of the ring 4 to retain the tumbler 14 and also to provide a seat for the tumbler 15. By virtue of its compactness or thinness, the improved lock is not only rendered neat and attractive in appearance, but it is adapted

for many useful applications for which a thicker or less compact lock construction would not be well suited.

Having fully described my invention, I claim:—

1. In a permutation lock, in combination, a case comprising a base plate, juxtaposed spacing rings adjacent the rear side of said base plate and a back plate imposed on said spacing rings, a sliding bolt arranged in co-planar relation to said base plate, a main tumbler also arranged in co-planar relation to said base plate and operative, by its rotation, to effect the projection of said bolt, an operating element arranged at the front side of said base plate and with which the main tumbler has operative rigid connection, a pair of rotatable annular tumblers, one of which is confined by the inner spacing ring against the rear side of the base plate and the other of which is co-planar with the outer spacing ring and is confined by the back plate against the inner spacing ring, the plate having a projection for co-operation with the main tumbler and having another projection for co-operation with the annular tumblers, all of said tumblers having peripheral recesses to receive the adjacent projections of said bolt and the annular tumblers being free of connection with said operating element, and co-acting means associated with said tumblers for transmitting rotary movement from one to another.

2. In a permutation lock, in combination, a case comprising a base plate, juxtaposed spacing rings adjacent the rear side of said base plate and a back plate imposed on said spacing rings, a sliding bolt arranged in co-planar relation to said base plate, a main tumbler also arranged in co-planar relation to said base plate and operative by its rotation to effect the projection of said bolt, an operating element arranged at the front side of said base plate and having a flat sided arbor, the main tumbler having a central opening conformable to the cross-section of said arbor and being removably fitted thereon, a nut holding the main tumbler on said arbor and holding the main tumbler and the operating element in relation to the base plate, a pair of rotatable annular tumblers, one of which is confined by the inner spacing ring against the rear side of the base plate and the other of which is co-planar with the outer spacing ring and is confined by the back plate against the inner spacing ring, the bolt having a projection for co-operation with the main tumbler and having another projection for co-operation with the annular tumblers, all of said tumblers having peripheral recesses to receive the adjacent projections of said bolt and the annular tumblers being free of connection with said operating element, and co-acting means associated with said tumblers.

for transmitting rotary movement from one to another.

3. In a permutation lock, in combination, a case comprising a base plate, juxtaposed spacing rings adjacent the rear side of said base plate and a back plate imposed on said spacing rings, a sliding bolt arranged in co-planar relation to said base plate, a main tumbler also arranged in co-planar relation to said base plate and operative by its rotation to effect the projection of said bolt, an operating element arranged at the front side of said base plate and having a flat sided arbor, the main tumbler having a central opening conformable to the cross-section of said arbor and being removably fitted thereon, a nut holding the main tumbler on said arbor and holding the main tumbler and the operating element in relation to the base plate, a pair of rotatable annular tumblers, one of which is confined by the inner spacing ring against the rear side of the base plate, and the other of which is co-planar with the outer spacing ring and is confined by the back plate against the inner spacing ring, the bolt having a projection for co-operation with the main tumbler and having another projection for co-operation with the annular tumblers, all of said tumblers having peripheral recesses to receive the adjacent projections of said bolt and the annular tumblers being free of connection with said operating element, and co-acting means associated with said tumblers for transmitting rotary movement from one to another, the means associated with the main tumbler including a disk having a central opening conforming to said arbor and removably fitted thereon, the disk being confined by said nut.

4. In a permutation lock, in combination, a case comprising a base plate, juxtaposed spacing rings adjacent the rear side of said base plate and a back plate imposed on said spacing rings, a sliding bolt arranged in co-planar relation to said base plate, a main tumbler also arranged in co-planar relation to said base plate and operative by its rotation to effect the projection of said bolt, an operating element arranged at the front side of said base plate and with which the main tumbler has operative rigid connection, a pair of rotatable annular tumblers, the base plate having a countersunk seat in its rear face for one of said annular tumblers and the said tumbler which fits in said seat being confined therein by the inner spacing ring, the other tumbler being co-planar with the outer spacing ring and being confined by the back plate against the inner spacing ring, the bolt having a projection for co-operation with the main tumbler and having another projection for co-operation with the annular tumblers, all of said tumblers having peripheral recesses to

receive the adjacent projections of said bolt and the annular tumblers being free of connection with said operating element, and co-acting means associated with said tumblers for transmitting rotary movement from one to another.

5. In a permutation lock, in combination, a case comprising a base plate, juxtaposed spacing rings adjacent the rear side of said base plate and a back plate imposed on said spacing rings, a sliding bolt arranged in co-planar relation to said base plate, a main tumbler also arranged in co-planar relation to said base plate and operative by its rotation to effect the projection of said bolt, an operating element arranged at the front side of said base plate and with which the main tumbler has operative rigid connection, a pair of rotatable annular tumblers, the base plate having a countersunk seat in its rear face for one of said annular tumblers and the said tumbler which fits in said seat being confined thereby by the inner spacing ring, the other tumbler being co-planar with the outer spacing ring and being confined by the back plate against the inner spacing ring, the bolt having a projection for co-operation with the main tumbler and having another projection for co-operation with the annular tumblers, all of said tumblers having peripheral recesses to receive the adjacent projections of said bolt and the annular tumblers being free of connection with said operating element, and co-acting means associated with said tumblers for transmitting rotary movement from one to another, the means comprising in the instance of the annular tumbler which adjoins the back plate a pair of inwardly directed, radial, oppositely disposed projections, in the instance of the other annular tumbler a pair of oppositely disposed projections which are directed toward the back plate and are arranged to engage said first-named projections, and in the instance of the main tumbler a pair of radial, outwardly directed, oppositely disposed projections which are arranged to engage the projections on the tumbler which adjoins the base plate.

6. In a permutation lock, in combination, a case comprising a base plate, juxtaposed spacing rings adjacent the rear side of said base plate and a back plate imposed on said spacing rings, a sliding bolt arranged in co-planar relation to said base plate, a main tumbler also arranged in co-planar relation to said base plate and operative by its rotation to effect the projection of the bolt, an operating element arranged at the front side of said base plate and with which the main tumbler has operative rigid connection, a pair of rotatable annular tumblers, one of which is confined by the inner spacing ring against the rear side of the base plate and

the other of which is co-planar with the outer spacing ring and is confined by the back plate against the inner spacing ring, the bolt having a projection for co-operation with the main tumbler and having another projection for co-operation with the annular tumblers, the main tumbler having a peripheral recess to receive the adjacent projection of said bolt and the annular tumblers each having a pair of peripheral recesses arranged adjacent and at the same side of a diameter and provided to receive the adjacent projection of said bolt, the annular tumblers being free of connection with said operating element, and co-acting means associated with said tumblers for transmitting rotary movement from one to another, the annular tumbler which adjoins the back plate being reversible whereby it may present either of its flat faces toward said back plate and in either of said positions being adjustable with relation to the other annular tumbler whereby it may present either of its recesses for registry with a selected recess of said other annular tumbler.

7. In a permutation lock, in combination, a case, a bolt slidably mounted therein and provided with projections, a pair of rotatable, annular tumblers arranged within said case in concentric relation, a rotatable main tumbler, an operating element rigidly connected with the main tumbler and free of connection with the annular tumblers, and co-acting means provided upon said tumblers for transmitting rotary movement from one to another and comprising in the instance of the outer annular tumbler, a pair of oppositely disposed, inwardly directed, radial projections, and in the instance of the inner annular tumbler, a pair of oppositely disposed projections directed toward the outer annular tumbler for engagement with the projections thereof, the main tumbler and the inner annular tumbler having recesses for co-operation with the adjacent projections of the bolt and the outer annular tumbler having a pair of recesses arranged adjacent to and at one side of a diameter to receive the adjacent projection of the bolt, said outer annular tumbler being reversible whereby it may present either of its flat faces toward the inner annular tumbler and in either of its said positions being adjustable with relation to the inner annular tumbler, whereby it may present either of its recesses for registry with the recesses of the inner annular tumbler.

8. In a permutation lock, in combination, a case comprising a base plate having at its front side a circumscribing marginal flange, juxtaposed spacing rings adjacent the rear side of said base plate and a back plate imposed on said spacing rings, a sliding bolt arranged in co-planar relation to said base plate, the flange having a slot for the head

of said bolt, a main tumbler also arranged in co-planar relation to said base plate and operative by its rotation to effect the projection of said bolt, an operating element arranged at the front side of said base plate and with which the main tumbler has operative rigid connection, a dial plate carried by said operating element and also arranged at the front side of said base plate, a pair of rotatable annular tumblers, one of which is confined by the inner spacing ring against the rear side of the base plate and the other of which is co-planar with the outer spacing ring and is confined by the back plate against the inner spacing ring, the bolt having a projection for co-operation with the main tumbler and having another projection for co-operation with the annular tumblers, all of said tumblers having peripheral recesses to receive the adjacent projections of said bolt and the annular tumblers being free of connection with said operating element, and co-acting means associated with said tumblers for transmitting rotary movement from one to another.

9. In a permutation lock, in combination, a case comprising a base plate having at its front side a circumscribing marginal flange, juxtaposed spacing rings adjacent the rear side of said base plate and a back plate imposed on said spacing rings, a sliding bolt arranged in co-planar relation to said base plate, the flange having a slot for the head of said bolt, a main tumbler also arranged in co-planar relation to said base plate and operative by its rotation to effect the projection of said bolt, an operating element arranged at the front side of said base plate and with which the main tumbler has operative rigid connection, a dial plate carried by said operating element and also arranged at the front side of said base plate, a pair of rotatable annular tumblers, one of which is confined by the inner spacing ring against the rear side of the base plate and the other of which is co-planar with the outer spacing ring and is confined by the back plate against the inner spacing ring, the bolt having a projection for co-operation with the main tumbler and having another projection for co-operation with the annular tumblers, all of said tumblers having peripheral recesses to receive the adjacent projections of said bolt and the annular tumblers being free of connection with said operating element, co-acting means associated with said tumblers for transmitting rotary movement from one to another, the dial plate having a marginal flange which is flush with the front face of the flange of said base plate and is spaced from said base plate, and a spring for retracting said bolt and arranged in the space between the flange of said dial plate and said base plate, one end of the spring being connected to said bolt and the

other end therecf being connected to the flange of said base plate.

10. In a permutation lock, in combination, a case comprising a base plate, a back plate and spacing means between the back plate and the base plate, a sliding bolt arranged in co-planar relation to said base plate, a main tumbler also arranged in co-planar relation to said base plate and operative by its rotation to effect the projection of said bolt, an operating element arranged at the front side of said base plate and with which the main tumbler has operative rigid connection, a pair of rotatable annular tumblers arranged in juxtaposed concentric relation adjacent the rear side of the base plate and between the latter and the back plate, the bolt having a projection for coöperation with the main tumbler and having another projection for coöperation with the annular tumblers, all of said tumblers having peripheral recesses to receive the adjacent projections of said bolt and the annular tumblers being free of connection with said operating element, and co-acting means associated with said tumblers for transmitting rotary movement from one to another.

11. In a permutation lock, in combination, a case comprising a base plate, a back plate and spacing means between the back plate and the base plate, a sliding bolt arranged in co-planar relation to said base plate, a main tumbler also arranged in co-planar relation to said base plate and operative by its rotation to effect the projection of said bolt, an operating element arranged at the front side of said base plate and with which the main tumbler has operative rigid connection, a pair of rotatable annular tumblers arranged in juxtaposed concentric relation adjacent the rear side of the base plate and between the latter and the back plate, the bolt having a projection for coöperation with the main tumbler and having another projection for coöperation with the annular tumblers, all of said tumblers having peripheral recesses to receive the adjacent projections of said bolt and the annular tumblers being free of connection with said operating ele-

ment, co-acting means associated with said tumblers for transmitting rotary movement from one to another, a dial plate carried by said operating element and arranged adjacent the front side of the base plate, the latter having an upwardly projecting, circumscribing marginal flange and the dial plate having a marginal flange in spaced relation to the base plate, and a spring for retracting said bolt arranged in the space between the marginal flange of the dial plate and the base plate and having one end secured to the flange of the base plate and the other end secured to said bolt.

12. In a permutation lock, in combination, a case comprising a base plate, a back plate and spacing means between the back plate and the base plate, a sliding bolt arranged in co-planar relation to said base plate, a main tumbler also arranged in co-planar relation to said base plate and operative by its rotation to effect the projection of said bolt, an operating element arranged at the front side of said base plate and with which the main tumbler has operative rigid connection, a pair of rotatable annular tumblers arranged in juxtaposed concentric relation adjacent the rear side of the base plate and between the latter and the back plate, the base plate having a countersunk seat for the inner of said annular tumblers, the bolt having a projection for coöperation with the main tumbler and having another projection for coöperation with the annular tumblers, all of said tumblers having peripheral recesses to receive the adjacent projections of said bolt and the annular tumblers being free of connection with said operating element, and co-acting means associated with said tumblers for transmitting rotary movement from one to another.

In testimony whereof I have hereunto set my hand in presence of two subscribing witnesses.

BUELL S. BURNETT.

Witnesses:

A. Y. MILAM,
ROBT. R. MILAM.
